MOUNTING FOR A RIFLE TELESCOPIC SIGHT

Donald R. Johannsen, Inkster, Mich., assignor to Wide-view Scope Mount Corporation, Inkster, Mich.

Filed May 26, 1972, Ser. No. 257,487

Term of patent 14 years

Int. Cl. D22—01

U.S. Cl. D22—7

FIG. 1

FIG. 2

FIG. 3

FIG. 4

FIG. 5

FIG. 1 is a top plan view of a mounting for a rifle telescopic sight showing my new design.

FIG. 2 is a side view thereof, the opposite side being a mirror image.

FIG. 3 is a front elevational view thereof, the rear elevational view being a mirror image.

FIG. 4 is a bottom plan view thereof.

FIG. 5 is a perspective view showing the front and side thereof.

I claim:

The ornamental design of a mounting for a rifle telescopic sight, substantially as shown and described.
